UNITED STATES PATENT OFFICE.

JEFFERSON A. G. HARTON, OF BROOKLYN, NEW YORK, ASSIGNOR TO BOORUM & PEASE COMPANY, OF BROOKLYN, NEW YORK, A CORPORATION OF NEW YORK.

LOOSE-LEAF BINDER.

Application filed May 9, 1923. Serial No. 637,634.

This invention relates to loose-leaf binders and has for its primary object to provide a device of this character which may be very easily and quickly manipulated for the insertion or removal of additional sheets or leaves.

It is another object of my invention to provide a binder of such a construction that one or more supplementary back sections 10 may be readily inserted when necessary in order to materially increase the capacity of the book or ledger.

It is a further object of the invention to provide an arrangement of the sheet or 15 leaf holding posts on the back sections of the binder so that said posts are relatively near the hinge line of the ledger covers, thus causing the sheets or leaves to lie perfectly flat when the ledger is open and enabling 20 the user to inscribe or write upon said sheets nearer to the post-receiving holes than is possible in devices of this character as heretofore constructed.

It is an additional object of the invention 25 to provide improved latch means for holding the complementary back sections in adjusted relation to each other and which may also be very easily operated to quickly effect the necessary adjustment.

30 With the above and other objects in view, the invention consists in the improved loose-leaf binder and in the form, construction and relative arrangement of its several parts as will be hereinafter more fully described, 35 illustrated in the accompanying drawings and subsequently incorporated in the subjoined claims.

In the drawings wherein I have illustrated a practical and desirable embodiment 40 of the invention and in which similar reference characters designate corresponding parts throughout the several views:

Figure 1 is an edge elevation of a loose-leaf ledger provided with one embodiment 45 of my improved binder;

Figure 2 is a sectional view taken on the line 2—2 of Figure 1, the leaves or sheets being omitted;

Figure 3 is a horizontal section taken on 50 the line 3—3 of Figure 1;

Figure 4 is a sectional view taken on the line 4—4 of Figure 3;

Figure 5 is a similar section taken on the line 5—5 of Figure 3;

55 Figure 6 is a detail elevation showing the

ledger open and illustrating another form of hinge connection between the cover members and the binder;

Figure 7 is a detail sectional view showing a slightly modified form of the binder 60 post;

Figure 8 is a similar view illustrating a modification of the latch keeper;

Figure 9 is a sectional view showing another form of the pivoted latch member; 65

Figure 10 is a view similar to Figure 1 but showing a supplemental back section inserted to increase the capacity of the ledger; and

Figure 11 is a perspective view of the supplemental back section. 70

In the drawings, I have illustrated a ledger of conventional form having cover members 5, which, in the construction shown in Figure 1, are connected to the rigid binder strips 6 by the leather hinges 7.

To the respective binder strips 6, the complementary binder sections 8 and 9 respectively, are secured. Each of these sections is formed from a sheet-metal plate, the section 8 having a back flange 10 and a relatively narrow flange 11 disposed at right angles to the flange 10 and suitably secured to one of the strips 6. The other section 9 has a similar back flange 12 and a flange 13 extending angularly from one edge thereof. As shown in Fig. 5 of the drawings, the flanges 11 and 13 of the binder sections are secured to the respective strips 6 by means of the screws 14 which have threaded engagement in sleeves 15 engaged in coinciding openings in the flanges and the strips 6. The inner ends of these sleeves are flanged as at 16. However, it will be apparent that various other means might be 85 employed for securing the sheet-metal binder sections to the strips 6 of the ledger. 90

The binder section 8 at the ends of its back flange 10 is bent inwardly to provide the grooves or channels 17 extending the 100 full height of the back flange, said back flange being angularly extended from said channels to provide the end flanges 18, each of which is formed with an inwardly projecting lug 19 securely riveted as at 20 105 to the flange 11.

Upon the outer side of each of the end flanges 18 a pivoted latch member 21 is mounted, the free end of said latch member being angularly disposed as at 22 and pro- 110

jecting inwardly through a slot 23 in the end flange 18. This hooked or angularly bent end of the latch member is yieldingly urged into one end of said slot, as by means of the leaf spring 24.

Upon the flange 11 of the section 8 spaced leaf-holding posts 25 are arranged, each of said posts being located substantially at the free longitudinal edge of the flange 11 and in line with each other. These posts likewise may be conveniently formed from sheet metal, and in a preferred embodiment, are of flat rectangular cross-section as seen in Figure 3 of the drawings, each post being provided with a base extension 26 riveted or otherwise securely fixed to the flange 11.

The other binder section 9 likewise has its back flange 12 bent upon itself at the ends thereof to provide ribs 27 for telescoping sliding engagement in the grooves or channels 17 of the binder section 8. From these ribs keeper flanges 28 project at right angles to the back flange 12, said keeper flanges at the ends thereof adjacent the flange 13, having notches or recesses 29. At their other ends, the keeper flanges are formed with the beveled or inclined edges 30. At their notched ends the flanges 28 are also formed with inwardly projecting lugs 31 which are riveted to the flange 13.

Upon the flange 13 spaced leaf-holding posts 32 of similar construction to the posts 25 are arranged, and when the two binder sections are assembled, the posts on one section are alternately disposed with relation to the post on the other section and in line therewith, it being understood that these posts engage through the openings in the ends of the leaves or sheets in the usual manner.

In the use of the improved binder as above described, the cover 5 and binder strip 6 carrying the binder section 8 is positioned upon the desk or table and the superposed sheets or leaves are arranged thereon with the posts 25 extending through two of the openings in each leaf. The other cover member 5 is then positioned upon the leaves and the ribs 27 of the binder section 9 are engaged in the channels or grooves 17 and said binder section forced downwardly so that its back flange 12 is disposed in overlapping relation with the flange 10 of the section 8 against the inner side thereof. The posts 32 of the section 9 of course, enter the other openings in the leaves or sheets. In this telescoping connection of the two binder sections, the inclined edges 30 on the keeper flanges 28 ride against the inwardly projecting ends 22 of the latch members 21, displacing said latch members from their normal position against the action of the springs 24 until the notches 29 in the flanges 28 coincide with the opening 23.

The inturned ends 22 of the latch members then snap into the notches 29 under the action of the springs 24, thus locking the two sections of the binder in assembled relation. It will be seen that by reason of this construction, the back of the binder is completely closed. When the ledger is opened, the leaves or sheets lie perfectly flat and in view of the fact that the posts 25 and 32 are located at the extreme edges of the flanges 11 and 13 respectively, and closely adjacent to the hinge line of the cover, the user may write upon the sheets very close to the post-receiving openings therein.

In order to add additional sheets or remove sheets from the ledger, it is only necessary for the user to move the ends of the latch members 21 to the right in the slots 23 thereby disengaging said members from the notches 29 so that the two complementary binder sections can be disconnected. After the removal of the leaves or insertion of new or additional leaves, the two sections can be again quickly connected in the manner above described. The parts are very rigidly held against relative shifting movement or the danger of accidental disconnection so that the ledger may be freely handled without liability of separation of the cover members from each other or the release or disarrangement of the superposed leaves or sheets.

In Figs. 6 to 9 inclusive of the drawings, I have illustrated alternatives for several of the structural features of the device above described. Thus, as seen in Fig. 6, instead of providing leather hinge connections between the cover members 5 and the binder strips 6, I may attach metal straps 33 and 34 to the members and strips respectively, and connect said straps by means of common pintle hinges 35.

In Fig. 7, I have illustrated another manner of attaching the leaf-receiving posts to the flanges of the binder sections. Thus, each of the sheet-metal posts may be provided at one of its ends with the angularly disposed spaced flanges 36 between which the edge of the flange on the binder section is received, said flanges being rigidly secured to each other by the rivet 37.

In Fig. 8 of the drawings I show the latch keeper flange as provided with a plurality of spaced notches 29' to receive the inwardly projecting hook on the latch member. Thus the two telescoping sections of the binder can be adjusted with relation to each other so as to increase the capacity of the ledger.

In Fig. 9, a slightly different form of the pivoted latch member is illustrated, said member being provided at its free end with an outwardly extending bend or loop 38 which projects slightly beyond the plane of the end edges of the binder strip 6 so that said loops or bends may be easily engaged.

by the fingers to move the latch members to release position when it is desired to open the binder.

Occasions may arise when it is desired to increase the capacity of the binder even beyond that which would be permissible when the means shown in Fig. 8 is provided for the relative adjustment of the two binder sections. In such instances, I employ a supplementary duplex binder section. As shown in Fig. 11 of the drawings, this supplementary section consists of two sections 8 and 9, identical as to structure with those hereinbefore described. These single sections 10 designated by the numerals 8' and 9' respectively, in Figure 11, are arranged with their back flanges disposed in the same plane and their attaching flanges in opposed contacting relation. These attaching flanges are 20 rigidly and permanently secured together by means of the rivets 39 which secure the leaf-engaging posts to the respective flanges and from which said posts project in relatively opposite directions and in staggered relation to each other.

When it is desired to increase the capacity of the ledger, it is only necessary to release the latch members 24 and lift the upper cover of the ledger and binder strip 6 carrying the binder section 9. The duplex supplementary section is then arranged in position, the end ribs on the part 9' thereof telescoping in the channels 17 of the other binder section to the strip 6. The additional 30 leaves or sheets are then arranged upon the upwardly projecting posts of the part 8' of the supplementary section and the cover 5 with the binder section 9 is then replaced, the latch members at the ends of the part 8' 40 engaging the keeper flanges as above referred to, while the latch members on the section 8 engage the keeper flanges on the part 9' of the supplementary section. Thus as will appear from Fig. 10 of the drawings 45 the several parts are securely locked together and provide a ledger of relatively large capacity. Of course, the capacity of the ledger might be even further increased by the use of another supplementary duplex 50 section of the form shown in Figure 11 of the drawings.

From the foregoing description considered in connection with the accompanying drawings, the construction, and manner of use of my improved loose-leaf binder will be clearly understood. Owing to the elimination of all 55 threaded post connections such as have heretofore been employed in devices of this character, it will be apparent that the binder can 60 be very easily and quickly opened and closed for the removal or insertion of sheets or leaves. The relatively simple and light construction of the several parts provides a binder which may be employed in connection 65 with very large books or ledgers without

unduly increasing the weight thereof and by the provision of the supplemental duplex sections each having the leaf-holding posts, the capacity of the ledger can be readily increased to any extent desired with the assurance 70 that all of the leaves or sheets will be held between the two cover members with the same degree of security. Also, it will be appreciated that the structure affording a sliding telescoping connection between the 75 several sections of the binder provides at all times a completely closed back for the ledger and renders the structure as a whole, very substantial and durable and resistant to 80 excessive strains.

I have herein referred to a construction of my improved loose-leaf binder which has been found in practice to give highly satisfactory service, nevertheless it is to be understood that the embodiments of the invention which I have selected for purposes of illustration may be susceptible of many other structural modifications than those herein referred to and I therefore, reserve the privilege of adopting all such legitimate 90 changes as may be fairly embodied within the spirit and scope of the invention as claimed.

I claim:

1. In a loose-leaf binder, complementary binder sections each having an attaching flange and a back flange, one of said sections being further provided with end flanges and channeled portions connecting the end flanges with the back flange, the other of 100 said sections having ribs at the ends of its back flange to telescopically engage in said channels and keeper flanges projecting laterally from said ribs, latch means on the end flanges of the first-named section to 105 engage said keeper flanges and lock the sections in assembled relation, and leaf-holding posts fixed to the attaching flange of each section.

2. In a loose-leaf binder, complementary 110 binder sections each consisting of a single sheet metal plate of L-shape form in cross section providing flanges extending at right angles to each other, one of said flanges constituting a back flange for the binder, the 115 said back flange of one binder section being bent at its opposite ends to provide channels therein, and the back flange of the other binder section at its opposite ends being bent to form channel engaging ribs thereon, manually operable latch devices mounted on the 120 opposite ends of the first named binder section, and latch engaging keeper means on the opposite ends of the second named binder section.

3. In a loose-leaf binder, complementary 125 binder sections each consisting of a single sheet metal plate of L-shape form in cross section providing angularly related flanges, one of which constitutes a back flange for 130

the binder, said back flange of one binder section being bent at its opposite ends to provide channels therein and terminal portions extending from said channels at substantially right angles to the back flange and fixed to the other flange of the binder section, the back flange of the other binder section being bent at its opposite ends to provide ribs thereon for telescopic engagement with the channels of the first named section and also having terminal portions projecting at right angles to said back flange and fixed to the other flange of said binder section, and manually operable latch devices mounted on the terminal portions of said first named binder section adapted to cooperate with the terminal portions of said second named binder section and detachably latch said sections in assembled relation.

4. In a loose-leaf binder, complementary binder sections each consisting of a single sheet metal plate of L-shape form in cross section providing angularly related flanges, one of which constitutes a back flange for the

binder, said back flange of one binder section being bent at its opposite ends to provide channels therein and terminal portions extending from said channels at substantially right angles to the back flange and fixed to the other flange of the binder section, the back flange of the other binder section being bent at its opposite ends to provide ribs thereon for telescopic engagement with the channels of the first named section and also having terminal portions projecting at right angles to said back flange and fixed to the other flange of said binder section, and spring pressed latch members pivotally mounted at one of their ends upon the terminal portions of the first named binder section and movable in parallel relation therewith and adapted to cooperate with said terminal portions of the second named binder section to detachably latch said sections in assembled relation.

In testimony that I claim the foregoing as my invention, I have signed my name hereunder.

JEFFERSON A. G. HARTON.
